Nelson W. Howard

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

HEEL-ATTACHING MACHINE.

Application filed July 20, 1922. Serial No. 576,286.

To all whom it may concern:

Be it known that I, JOSEPH H. POPE, a citizen of the United States, and resident of Hamilton, in the county of Essex and State of Massachusetts, have invented certain Improvements in Heel-Attaching Machines, of which the following description, in connection with the accompanying drawings, is a specification, like reference characters on the drawings indicating like parts in the several figures.

My invention relates to machines for the attachment of heels, it being particularly adapted for use in connection with heels carrying devices which are to secure them.

A heel of this character and of the Louis type is illustrated in the patent to Finberg, No. 1,296,939, dated March 11, 1919, it having projections from the upper end adapted to be forced through the heel-seat of a shoe and clinched over the insole. An object of this invention is to provide improved means for the effective application of pressure during the attachment of such heels. In the attainment of this object, the heel is engaged only by contact with its sides, this, in a Louis heel, for example, being over the enlarged portion adjacent to the heel-seat. This hold upon the heel is independent of the varying angles between the heel-seat and tread-surfaces for different sizes and styles, and also presents for these changes relatively slight differences in dimensions of the surface engaged. Such differences as exist may be compensated for by making a portion of the engaging means yieldable. In the form of my invention illustrated, the shoe to be heeled is supported upon a jack movable into and out of attaching position, and there is an opposed heel-engaging member, which is open at the side toward the jack to receive the heel positioned upon the jacked shoe ready for attachment, while the contact-surface of this member, which applies the pressure, is curved for engagement with the sides of the heel.

In the attachment of the above-mentioned heels, in fact of any form heel, difficulty may be encountered in producing a tight joint at the rand-crease, the best results following the clinching of the attaching prongs outwardly from the center of the heel-seat toward the counter of the shoe. Another object of my invention is to insure the desired direction of clinch, an effect which I

obtain by means associated with the support. As illustrated herein, the jack carrying a shoe for the heeling operation has a surface for supporting said shoe, and surfaces inclined to the supporting surface for engagement with the points of the prongs or other attaching devices, these surfaces being relatively movable. The inclined surfaces, which act on the points of the attaching devices, may be upon deflecting members operating in openings in the jack in alignment with said attaching devices, being shown as upon upward projections from the jack, while the shoe-support may consist of a plate surrounding the projections and being movable to yield along them.

These and other objects of the invention are achieved by the employment of the apparatus hereinafter described and illustrated in the accompanying drawing, in which—

Fig. 1 represents, in front elevation, the more essential portions of a machine constructed in accordance with the present invention;

Fig. 2 is a side elevation, looking from the right in Fig. 1;

Fig. 3 is a partial top plan view;

Fig. 4, a plan view of the top of the jack; and

Fig. 5, a vertical section on the line 5—5 of Fig. 4.

There may be utilized, for the actuating elements of my improved machine and the structure supporting them, the organization disclosed in the patent in my name numbered 446,885 and dated February 24, 1891. From this, the top girt carrying the drivers and the part which produces its movement may be omitted, and the die 10 becomes an attaching member in the form of a pressure-resisting bar or abutment carried upon standards 12, 12. Depending from the under side of the bar 10 is a heel-engaging member 14 secured in place by screws 16, 16 passing vertically through openings in the bar and being threaded into the engaging member. This member is further positioned by a tongue and groove 18 formed in it and in the under side of the bar. In the member 14 is a heel-receiving cavity 20, open at its front and having its upper portion of such dimensions that a heel may be positioned within it without contact with the adjacent walls. At the lower portion of the member, the cavity 20 has a contact-

surface 22 curved both vertically and horizontally to correspond in contour to the enlarged portion of a heel, illustrated at H, between the heel-seat-end and the reduced neck. The heel is shown as provided at said heel-seat-end with prongs or attaching devices h. Since, as the heels vary in size and style, the dimensions of this enlarged portion change somewhat, though not very greatly, there is preferably applied to the surface 22 a layer of yieldable material 26, which may be rubber vulcanized to the surface 22, or felt secured in place by an adhesive. This lining conforms under pressure to the contour of the heel with which it contacts, and thus allows the proper action of the abutment upon a wide range of heels without change in the member 14.

The jack or work-support 28 is mounted, as in the patent previously mentioned, for movement vertically, under the influence of power mechanism, toward and from the engaging member 14, and also is movable horizontally by the operator manually to carry the jack from the work-receiving position to that in which it is operated upon, and the reverse. In this movement into the operating position, the initial relation between the work and the heel-engaging member 14 may be determined by a back-stop 30 arranged for engagement with the counter-portion of a shoe S, carried by the jack 28, to which a heel is to be attached. This back-stop is preferably adjustable, it having, extending rearwardly from its upper extremity, a horizontal screw-portion 32 guided in the frame of the machine and having threaded upon it a nut 34 turning between cheeks or abutments on the frame. This permits the back-stop to be altered in its horizontal relation to the heel-engaging member to position work varying in size in the desired relation thereto.

Rising from the top of the jack and aligned respectively with the heel-prongs h when the heel is in place upon the heel-seat of the shoe, ready for attachment, are projections 36, which may be furnished by pins having heads or enlargements 38 resting upon the top of the jack. These pins are held in place by a plate 40 fixed to the jack and having recesses which receive the heads of the pins, and openings through which said pins pass. The upper ends of the pins are inclined at 42, with respect to their axes, in the direction in which the attaching prongs are to be clinched. As illustrated, this inclination is from the center of the heel-seat of the shoe downwardly and outwardly, so that the points of the prongs will be turned toward the rand-crease and tend to increase the closeness with which the edge of the heel is held to the upper. Upon the top of the jack, above the plate 40, is a horizontal plate 44 having open-

ings 46 which the pins enter. Between the plates 40 and 44, and encircling the pins 36, are helical springs 48, which yieldably hold the plate 44 with its upper shoe-supporting surface elevated above the inclined ends 42 of the pins. The upward movement of the plate 44, under the influence of the springs, may be limited by screws 50, which pass through openings in said plate 44 and are threaded into the plate 40. Counter-bores 52 in the first-mentioned plate receive the heads 54 of these screws, contact between the screw-heads and the bottoms of the counter-bores limiting the travel of the plate 44.

In attaching a heel H to the shoe S, the proper relation between the elements may be first determined, and openings pricked in the heel-seat to receive the ends of the prongs h. The operator then places the shoe upon the jack, which is in its outer position removed from the engaging member 14, with the insole at the heel-seat resting upon the plate 44, and inserts the prongs in the pricked openings. Now the jack may be carried into the operating position, as is illustrated in Fig. 1 of the drawing, the space between the jack-top and the pressure-resisting member 10 being such that the positioned heel may enter the cavity 20 with its enlarged surface in proximity to the yieldable lining 26 of the abutment-surface 22, movement of the jack and shoe being limited by the back-stop 30. Upon the treadling of the machine by the operator, the jack rises under the influence of the power mechanism, and, the heel being held against movement both vertically and horizontally by the engaging member 14, the prongs h are forced through the heel-seat against the inclined surfaces 42 of the pins 36. The resistance to compression offered by the springs 48 is sufficient to at this time prevent the approach of the plates 40 and 44, so that before the heel-seat of the shoe and the surfaces 42 move toward each other, the points of the prongs are turned outwardly and then upwardly by the inclined surfaces and the adjacent walls of the openings in which they operate, putting them in the correct relation to enter the sole for clinching. Then, the attaching pressure continuing, the springs are compressed, and the upturned points of the prongs are carried through the sole at the side toward the rand-crease, and are clinched in said sole.

Having described my invention, what I claim as new and desire to secure by Letters Patent of the United States is:

1. In a machine for attaching heels having projections, an engaging member arranged to contact with a heel at the sides only, and means arranged to apply pressure to the engaged heel and a shoe and to contact with the heel-projections to effect the attachment.

2. In a machine for attaching Louis heels, an engaging member arranged to contact with the heel solely over the enlarged portion adjacent to the heel-seat, a jack for the shoe 5 to be heeled, and automatic means for moving the jack to apply pressure to the engaged heel and a shoe to effect the attachment.

3. In a machine for attaching pronged heels, an engaging member having a yieldable portion arranged to contact with a heel at the sides only, and mechanism for applying pressure to the engaged heel and a shoe and having means contacting with the prongs to effect the attachment.

15 4. In a machine for attaching pronged heels, a jack and an attaching member relatively movable to exert pressure upon the work and having portions arranged to contact with the heel-prongs, and an engaging member carried by the attaching member and arranged to contact with the sides of the heel during the application of pressure.

25 5. In a heel-attaching machine, a jack movable into and out of attaching position, a heel-engaging member open at the side toward the jack and having a curved wall for engagement with the sides of a heel, and means arranged to effect the attachment of the engaged heel by movement of the jack 30 while in attaching position.

35 6. In a heel-attaching machine, a jack movable into and out of attaching position and arranged to carry a shoe and heel to be attached thereto, a heel-engaging member open at the side toward the jack to admit a heel in the movement of said jack and having a curved wall for engagement with the sides of a heel, and a back-stop arranged for contact with the counter-portion of a jacked 40 shoe and positioning the heel for its entrance into the engaging member.

45 7. In a machine for attaching Louis heels, a crossbar, an abutment member depending therefrom and having a contact-surface to engage the enlarged portion of a heel and a space to admit the tread-portion, and a jack movable toward and from the abutment.

8. In a heel-attaching machine, a shoe-sup-

port, means opposite the support for holding a heel and its attaching devices, means for 50 moving the support and holding means relatively to effect the attachment, and means associated with the support for determining the direction in which the attaching devices shall be inserted in the shoe.

55 9. In a heel-attaching machine, a jack having a shoe-supporting surface and surfaces inclined to the supporting surface and arranged to engage the points of the attaching devices, such supporting and engaging surfaces being relatively movable.

10. In a heel-attaching machine, a jack having openings to receive the attaching devices, and deflecting members operating in the openings in alinement with the attaching 65 devices.

11. In a heel-attaching machine, a jack having upward projections for engagement with the attaching devices, and a shoe-supporting plate surrounding the projections 70 and being movable with relation thereto.

12. In a heel-attaching machine, a jack having upward projections provided with outer ends inclined to the axes of the projections, and a plate having openings to receive the projections and being mounted to yield along said projections.

13. In a heel-attaching machine, a jack, pins projecting from the top of the jack and having their upper extremities inclined to 80 the axes of said pins, a plate having openings to receive the pins, and springs interposed between the jack and plate.

14. In a heel-attaching machine, a jack, pins projecting from the top of the jack and 85 having their upper extremities inclined downwardly and outwardly, a shoe-supporting plate having openings to receive the pins, and springs interposed between the jack and plate and arranged to hold the supporting 90 surface of said plate normally above the inclined ends of the pins.

In testimony whereof I have signed my name to this specification.

JOSEPH H. POPE.
